DESIGN FOR A DRESS

Blanche Price, Chicago, Ill.

Application October 4, 1940, Serial No. 95,645

Term of patent 3 1/2 years

To all whom it may concern:

Be it known that I, Blanche Price, a citizen of the United States, residing at 433 Wrightwood Ave., Chicago, in the county of Cook and State of Illinois, have invented a new, original, and ornamental Design for a Dress, of which the following is a specification, reference being had to the accompanying drawing, forming part thereof.

The characteristic feature of my design resides in the combination on the specific dress disclosed of the vertical bands of contrastingly colored fabric arranged on each side of the yoke above the pockets, as shown.

I claim:

The ornamental design for a dress, substantially as shown and described.

BLANCHE PRICE.
